UNITED STATES PATENT OFFICE

128,644

DESIGN FOR AN ALPHABET FOR FORMING MONOGRAMS OR THE LIKE

Clifton Louis Rush, Louisville, Ky.

Application March 18, 1941, Serial No. 99,678

Term of patent 7 years

To all whom it may concern:

Be it known that I, Clifton Louis Rush, a citizen of the United States, residing at Louisville, in the county of Jefferson and the State of Kentucky, have invented a new, original, and ornamental Design for an Alphabet for Forming Monograms or the Like, of which the following is a specification, reference being had to the accompanying drawing, forming part thereof.

Fig. 1 is a plan view of the alphabet for forming monograms or the like, showing my new design; and

Fig. 2 is a perspective view on an enlarged scale, and for the purpose of showing a third dimension of the letter "M" the same being typical of all the letters.

I claim:

The ornamental design for an alphabet for forming monograms or the like, substantially as shown and described.

CLIFTON LOUIS RUSH.
